UNITED STATES PATENT OFFICE.

BENJAMIN L. WALKER, OF SING SING, NEW YORK.

IMPROVEMENT IN LAWN-MOWERS.

Specification forming part of Letters Patent No. 131,726, dated September 24, 1872; antedated September 21, 1872.

To all whom it may concern:

Be it known that I, BENJAMIN L. WALKER, of Sing Sing, in the county of Westchester and State of New York, have invented certain new and useful Improvements in Mowing-Machines, of which the following is a specification:

This invention relates more particularly to what are known as rotary hand lawn-mowers, though it may be applicable, wholly or in part, to other rotary mowing-machines. It consists in the arrangement of the cutter-reel to which the rotary cutters are attached, upon the same axle with the wheels of the machine, and in a novel arrangement of the fixed cutter, in combination with which the rotary cutters operate, whereby the cutting of the grass to a more nearly uniform length on uneven or rolling ground is effected. It also consists in a novel arrangement of gearing, driving the rotary cutter-reel with very little friction; also, in novel means of providing for the adjustment of the cutters to cut closer to or not so close to the ground.

Figure 1, in the accompanying drawing, represents a vertical section taken at right angles to the axle, of a hand lawn-mower with my improvements applied; Fig. 2 is a plan view of the same; Fig. 3 is a vertical section of the same taken lengthwise and centrally through the reel and wheels; and Fig. 4 is an inside face view of the driving-wheel and corresponding face view of the gearing for driving the reel.

Similar letters of reference indicate corresponding parts in the several figures.

A is the driving-wheel, and B a supporting-wheel of corresponding size, secured one on one end and the other on the other end of an axle, C. These wheels are hollow, the cavities being on their inner sides, and each has fitted loosely within its rim a disk, D. These disks are fitted loosely to the axle C, and have firmly secured to them two arms, E E, to which is secured a cross-bar, F, which is parallel with the axle, and to which is secured the tongue G by which the machine is driven, the operator taking hold of this tongue and pushing the machine before him. The disks D D, arms E E, and cross-bar F may be considered as the framing of the machine. H is the fixed

cutter-bar, to which the fixed cutter a is attached, extending across the lower part of the space between the wheels, and bolted firmly to the lower parts of the disks D D by a screw-bolt, b, at each end, the said bolts passing through slots in the disks and screwing into tapped holes in lugs c c, which are provided on the ends of the bar, and which are fitted between guides d d (see Fig. 1) on the faces of the disks. This mode of attachment of the cutter-bar provides for its adjustment nearer to or further from the axle, that the rotary cutters may work more or less close to it. The cutter a is bolted to the upper face of the bar H, and presents its edge in a forward direction. I is the cutter-reel, made with arms at each end of its hub and having spirally-arranged bars e e attached to the said arms, and extending all across it for the attachment of the cutters f f, which are of ordinary construction. The hub of the reel extends the whole length of that portion of the axle between the disks D D, and is bored to fit loosely to the axle C, that it may rotate thereon. The driving-wheel A has formed on or secured to it, within its rim, an internally-toothed spur-gear, J, which gears with a spur-gear, K, fitted to turn loosely on a stud, g, secured firmly to the disk D that is fitted within the driving-wheel, and this gear K gears with a similar gear, L, turning loosely on a stud, h, also secured firmly to the same disk D; and this gear L gears with a spur, M, which is fitted to turn loosely on the axle C. This gearing is all inclosed between the driving-wheel and its disk D. The hub of the gear M is extended into a counterbore in the adjacent end of the reel, and has teeth i cut in its inner end to make it form a portion of a ratchet-clutch, the other portion j of which is fitted loosely to the axle, and so fitted into the reel with a feather, k, as shown in Fig. 4, or otherwise, that it may slide freely in and out of gear with the gear M, but that when it turns the reel is compelled to turn with it, and a spring, l, is applied within the reel at the inner end of the portion j of the clutch, which tends to keep it in gear.

The operation is as follows: As the machine is pushed along over the ground the wheels A B are caused to rotate by the traction and to

produce rotary motion of the axle. The rotation of the internally-toothed spur-gear J with the driving-wheel A produces the rotation of the gear K, through it the rotation of the gears L and M, and the last-mentioned wheel transmits, through the clutch *i j*, its rotary motion to the reel, by which the cutters *f f* are caused, acting in combination with the fixed cutter *a*, to produce their cutting operation. The motion thus transmitted to the cutter-reel is in the same direction with that of the axle, and hence the friction of the reel on the axle is much less than if their rotation were in opposite directions, or than if the axle did not rotate at all. In case of the machine being drawn backward the spring *l* allows the beveled teeth of the clutch to pass each other without giving motion to the reel; and, in case of the machine being stopped suddenly, the said spring allows a similar action of the teeth of the clutch and allows the reel to continue its rotation until its momentum expires, and thereby prevents injury to the gearing, which might otherwise result from a sudden stoppage.

In order to provide for the cutting of the grass more or less close to the ground the cross-bar F, to which the tongue is attached, is made adjustable higher or lower in slots *m* (see Fig. 1) provided in the said arms for its reception, the bar being squared to fit the said slots in such manner that it will not turn therein, and being secured therein by nuts *n n* fitted to screws formed on its ends, the said nuts clamping the arms against shoulders on the bar. By lowering the bar F the cutter is thrown forward and downward to a position more nearly under the axle, and so brought nearer to the ground and the cutting of the grass caused to be more close; and by raising the bar an opposite effect is produced.

Owing to the position of the cutter *a* being

brought so nearly under the axle by the arrangement of the reel on the main or driving axle the accidental variations in the axle between the tongue and the ground that occur in running over hilly, uneven, or rolling land, have a very slight effect on the position of the cutter *a*, relatively to the ground, compared with what they have when the rotary cutter-reel works on a separate axle; and, besides, the arrangement of the reel on the main axle makes the machine simpler and more compact.

Claims.

1. The arrangement of the rotary cutter-reel upon the same axle with the driving and supporting wheels of the machine, substantially as and for the purpose herein described.
2. The fixed cutter *a* arranged directly below the axle of the driving or supporting wheels on disks or carriers D D hung directly on the said axle, in combination with rotary cutters on a reel rotating on the said axle, substantially as herein described.
3. In combination with the cutter-reel rotating upon the main or driving axle, I claim the internally-toothed gear J on the driving-wheel, the loose gear M on the axle connected by a ratchet-clutch with the reel, and the intermediate gears L M attached to the disk or cutter-bar carrier D, substantially as herein described.
4. In combination with the fixed cutter *a*, arranged as described, and the cutter-reel rotating on the main axle, I claim the bar F adjustable in the slotted arms E E attached to the cutter-bar carriers D D, substantially as herein described, and for the purpose set forth.

BENJN. L. WALKER.
